UNITED STATES PATENT OFFICE.

AUGUSTUS E. SCHLIEDER, OF BUFFALO, NEW YORK, ASSIGNOR TO MONARCH ACETYLENE GAS COMPANY, OF OMAHA, NEBRASKA, A CORPORATION OF NEBRASKA.

CARBID-FEED MECHANISM.

965,756.

Specification of Letters Patent. Patented July 26, 1910.

Application filed October 2, 1907. Serial No. 395,576.

To all whom it may concern:

Be it known that I, AUGUSTUS E. SCHLIEDER, a citizen of the United States, residing at Buffalo, in the county of Erie and State 5 of New York, have invented certain new and useful Improvements in Carbid - Feed Mechanism, of which the following is a specification.

This invention relates to improvements in 10 carbid feed-mechanism.

In carbid feed-mechanisms now in use, the feed-valve is generally open to its full extent when the gas - bell of the gas - holder is at a predetermined low point, which position the gas-bell assumes when the gas with 15 in the holder is consumed, or almost consumed, and the feeding of carbid to the gas-generator ceases. Cessation of the feeding action oftentimes occurs when the carbid 20 bridges or clogs within the carbid receptacle, and experience has shown that the controlling mechanism between the feed-valve and gas-bell is liable to become disarranged or temporarily ineffective in the performance 25 of its proper functions. At such times, excessive generation of gas is likely to take place, which is not only wasteful, but dangerous as well. When the carbid is bridged within its containing - receptacle and the 30 valve is open, the entire contents of the carbid-receptacle, or at least an excessive quantity of carbid, is likely to be charged into the gas generating - chamber on the slightest jarring of the machine, causing 35 generation of gas considerably in excess of the capacity of the machine. When the controlling mechanism fails to properly respond to the action of the gas-bell, overcharging of the gas-generating-chamber is 40 also likely to occur, and serious accidents result therefrom. Overcharging of the carbid into the generating-chamber is known to be dangerous, and provision has been made to avoid this during the proper operation of 45 the machine.

It is the purpose of my invention to avoid overcharging at all times, and for this purpose I provide an auxiliary-valve or closure for the carbid-receptacle operated by the 50 primary or feed-valve, and so arrange the same that when the primary or feed-valve is open to its full extent, or if desired to any predetermined point, the auxiliary-valve is moved to close the outlet of the carbid-receptacle. It has also been found that, when

first starting the generation of gas by hand to set the machine in operation, the operator may carelessly open the feed-valve unnecessarily wide, which permits the carbid to drop into the gas generating - chamber in 60 larger quantities than desired, causing overcharging of the gasometer with the generated gas, which is not only wasteful, but dangerous as well.

To these ends the invention consists in 65 automatically - controlled mechanism for closing the outlet of the carbid-receptacle when the feed-valve is open and its controlling-mechanism fails to close the same; and in controlling-mechanism which limits the 70 extent of rotation of the valve-shaft when starting the generation of the gas; and it further consists in the construction, arrangement, and combination of parts to be herein-after described and particularly pointed out 75 in the appended claims.

Referring to the drawings,—Figure 1 is a side elevation of a valve-chamber located in a gas-generator between the carbid - receptacle and the gas generating-chamber, and 80 the controlling mechanism which controls the feed of carbid to the gas-generating-chamber, and showing also a portion of the carbid-receptacle, the gas-generating chamber, and gasometer. Fig. 2 is a side elevation of the valve-chamber with a part broken away. Fig. 3 is a vertical section taken on line 3—3, Fig. 2. Fig. 4 is a horizontal section taken on line 4—4, Fig. 1. Fig. 5 is a vertical section taken on line 5—5, Fig. 3. 85 Fig. 6 is a sectional elevation similar to Fig. 2, with the valves in inverse relation; the valve-chamber only being shown. Fig. 7 is 90 an enlarged detached perspective view of the primary or feed-valve. Fig. 8 is an enlarged perspective view of the auxiliary-valve or closure. Fig. 9 is a horizontal section taken on line 9—9, Fig. 1. Fig. 10 is a top plan view of the controlling lever and horizontal section through the adjacent portion of the gasometer, the stop-pawl of the controlling-lever being swung outward to 95 limit the movement of the lever. Fig. 11 is a side elevation of the controlling lever with its parts in normal or locked position. Fig. 105 12 is a perspective view of the controlling-lever with its parts arranged to limit the movement thereof. Fig. 13 is a cross-section taken on line 13—13, Fig. 11. Fig. 14 is a cross-section taken on line 14—14, Fig. 11. 110

Fig. 15 is a detached perspective view of the stop-pawl.

Referring to the drawings in detail, like numerals of references refer to like parts in 5 the several figures.

The numeral 10 designates the valve-chamber, usually located between the carbid-receptacle 11 and the gas-generating chamber 12, into which latter the carbid is to be 10 charged in proportion to the consumption of gas.

13 designates the gas-bell having a slotted vertical rod 14 secured thereto, as is common 15 in gas-generators. Extending into the upper end of the valve-chamber 10 is a 20 hopper 15 open at its lower end. This hopper is an extension of the carbid-receptacle and forms part thereof. An oscillating segmental feed-valve 16 is movable back and forth underneath the hopper to open and 25 close the same; it having radial arms 17, to one of which is secured the end of an operating or valve-shaft 18 forming part of controlling-mechanism 19 and passing through 30 a stuffing-box 20 in the wall of the valve-chamber. Formed on the other of said radial arms is a stub-shaft 21 having its axis coincident with the axis of said operating or valve-shaft and being journaled in a 35 bracket or support 22 secured to the wall of the valve-chamber. Secured to the operating-shaft 18 is a controlling-lever 23 which enters a slot 24 in rod 14, and therefore, 40 when the gas-bell rises or lowers, said shaft is rocked, causing the feed-valve to oscillate underneath the hopper 15 to open or close the outlet of the carbid-receptacle; the extent of opening being in proportion to the consumption of gas when the machine and its various parts are in proper working order.

When the carbid in the carbid-receptacle and the generated gas in the gas-bell is consumed, or when the carbid bridges or clogs 45 in the carbid-receptacle and fails to feed, the gas-bell gravitates to its lowest point, causing the feed-valve to open to its full extent through the intervention of the controlling mechanism. In gas-generators now in 50 use, it is necessary to provide means to prevent the replenishing of the carbid-receptacle until the feed-valve or mechanism is closed, necessitating the use of expensive and complicated mechanism between the controlling-mechanism and the cover or inlet closure 55 of the carbid-receptacle. Such means, while it avoids the carbid when fed into the carbid-receptacle, falling directly into the generating-chamber, it does not prevent the 60 accidental and excessive feeding of the carbid on a slight jar of the machine in the event of the carbid bridging or clogging within the receptacle; or when for any other reason, casual cessation of the feeding of 65 carbid takes place.

To eliminate the above mentioned and other objections, I provide means for closing the outlet of the carbid-receptacle when the feed-mechanism is moved to a certain point within the range of its movement, 70 which point may be predetermined and actuation of said closure-means caused when the valve is only partly open, or when open to its full extent, as may be found desirable in each case; depending also on the type of 75 feed-valve used and the extent and direction of its movement. This closure means is in the form of mechanism comprising a rock-spindle 25 journaled in a bracket 26 on the wall of the valve-chamber and having secured thereto a curved auxiliary valve or closure 27 which is normally inactive, as shown in Fig. 6, and adapted to be swung against the outlet of the carbid-receptacle when the feed-valve is open, as shown in 80 Figs. 2 and 5. Said auxiliary-valve or closure is actuated by an extension or arm 28 on the feed-valve or the operating-shaft, as may be desired; said arm having a laterally extending toe 29 and its end curved, as at 30; 85 said curved end being in an arc of a circle having its axis coincident with the axis of the operating-shaft. Secured to rock-spindle 25 is an arm 31 having a curved edge 32 corresponding with the curved end of 90 arm 28.

When the feed-valve is opened to a certain point, the toe on the arm 28 comes in contact with the curved edge 32 of arm 31 and raises the latter, causing the closure or 100 auxiliary-valve 27 to swing upward against the outlet of the carbid-receptacle to close the same. When said auxiliary-valve is closed, the curved arm 28 is in contact with the curved edge of arm 31, and as the 105 contacting surfaces correspond, the feed-valve is free to move while holding the closure or auxiliary-valve in its closed position.

The controlling-lever 23 comprises two-lever members, 33 and 34, a lock-member 35 110 whereby the two-lever members are held in locked condition, and a stop-member 36. Lever-member 33 is secured at a point between its ends to the operating-shaft and at one end it has a laterally extending finger-piece 37 by means of which the shaft may be operated manually, which is necessary when starting the machine in operation. The opposite end of said lever member is curved downward, as at 38, and has pivotally attached thereto lock-member 35 which has a long-arm 39, a short-arm 40 through which is passed the pivot pin by means of which said lock-lever is attached to lever-member 33, and a connecting-arm 41 arranged at an 115 angle to arms 39 and 40.

The lever-member 34 is loosely mounted on the operating-shaft and extends with its outer end beyond the corresponding end of lever-member 33 so as to enter the slot in 120

the rod 14 secured to the gas-bell. Normally, lever-member 34 is locked to member 33 by the lock-member 35, as shown in Fig. 11; the rear end of member 34, entering the space between the long and short arms of the lock member and having its extremity rounded, as at 45, to act against the curved lower edge 46 of the long arm of said lock-member to raise the latter out of locking position which permits manual actuation of the valve-shaft without regard to the position of the gas-bell or the actuation of the same. Said lock-member is provided with a toe 47 designed to strike a stop 48 projecting laterally from the inner extremity of lever-member 33 for the purpose of limiting the upward movement of the lock-member. A retractile spring 49 having its ends attached to the lock-member and lever-member 33, respectively, serves to retain the lock-member in locking position when the lever-member 34 is swung into normal position with respect to its coöperating lever-member 33. The lower edge of the lock-member has the axis of its curved edge coincident with the axis of the valve-shaft so that when lever-member 33 is actuated to rock said shaft, the lock-member travels back and forth in contact with the end of lever-member 34 without changing its position on lever-member 33.

The outer free end of the long arm of lock-lever 35 is enlarged and slightly curved at its extremity to permit of conveniently raising the same by placing the thumb thereagainst and exerting an upward pressure thereon.

Lock-member 35 has pivotally secured thereto, stop-member 36 by a pivot-pin or screw 50 passing through said stop-member and taking into the upper edge of the lock-member. A stop 51 in the form of a lip extends from the upper edge of said lock-member and serves to limit the swinging movement of said stop-member, which latter has at its inner or pivotal end a notch 52 providing abutments 53 and 54 which strike stop 51. When the several parts of the controlling-lever are in normal position, stop-member 36 lies over the lock-member as shown in Fig. 9 but on swinging the lock-member upward to permit independent movement of lever-member 33, the stop-member swings outward at an angle to said lock-member and in the path of a stop or projection 55 on the gasometer, designated 56 in which the gas-bell is confined. By this arrangement, the valve-shaft is limited in its rocking-movement when manually actuated to set the machine in operation, and consequently the carbid is fed from the carbid-receptacle into the gas-generator in small quantities, the opening of the feed-valve being in proportion to the extent of movement of the valve-shaft.

My invention is susceptible to many changes in form, construction, and arrangement of parts without departing from the spirit or sacrificing any advantages thereof.

Having thus described my invention, what I claim is,—

1. The combination with a gas-bell, a carbid-receptacle, and a gas-generating chamber, of a shaft oscillatable on the rise and fall of said gas-bell, a segmental-valve on said shaft adapted to open and close the outlet of the carbid-receptacle, an arm extending outward from the axis of said shaft and said valve, a spindle suitably mounted to rock, a closure rigid on said spindle, and an arm on said spindle in the path of the first mentioned arm and adapted to be engaged by the latter to cause the closure to swing against the outlet of the carbid-receptacle and close the same. 85

2. The combination with a gas-bell, a carbid-receptacle, and a gas generating-chamber, of a shaft oscillatable on the rise and fall of said gas-bell, a segmental-valve on said shaft adapted to open and close the outlet of the carbid-receptacle, an arm extending outward from the axis of said shaft and said valve and having its outer end curved, a spindle suitably mounted to rock, a closure rigid on said spindle, and an arm on said spindle having a curved edge adapted to be engaged by the curved end of the first mentioned arm when the feed-valve reaches a certain point in its opening movement so as to cause said closure to swing against the outlet of the carbid-receptacle and close the same. 90

3. The combination with a gas-bell, a carbid-receptacle, and a gas generating chamber, of a shaft oscillatable on the rise and fall of said gas-bell, a segmental-valve on said shaft adapted to open and close the outlet of the carbid-receptacle, an arm extending outward from the axis of said shaft and said valve and having a laterally extending toe at its outer end and said end curved, a spindle suitably mounted to rock, a curved closure rigid on said spindle, and an arm on said spindle having a curved edge adapted first to be engaged by the toe on said first-mentioned arm and then by the curved end of the latter arm to cause the closure to swing against the outlet of the carbid-receptacle and close the same. 110

4. The combination with a gas-bell, a carbid-receptacle, and a gas generating-chamber, of a shaft oscillatable on the rise and fall of said gas-bell, a segmental-valve on said shaft adapted to open and close the outlet of the carbid-receptacle, an arm extending outward from the axis of said shaft and said valve, and having a laterally extending toe at its outer end curved in an arc of a circle having its axis coincident with the axis of the said shaft, a spindle suitably mounted 120

125

130

to rock, a curved closure rigid on said spindle, and an arm on said spindle having a curved edge corresponding with the curved outer end of the first mentioned arm, the 5 arm on said spindle being adapted to be engaged first by the toe on said first-mentioned arm to cause the closure to swing against the outlet of the carbide-receptacle and then be engaged by the curved end of the latter arm 10 to permit movement of the valve after the closure has closed the outlet of the carbide-receptacle.

5. The combination with a carbide-receptacle, a gas generating-chamber, and a gasometer having a gas-bell, of a valve controlling the feed of carbide to said gas generating-chamber, a rock-shaft to which said valve is secured, and a controlling-lever comprising two parts normally locked together, one of said parts being loosely mounted on said shaft and in operative connection with the gas-bell and the other part being affixed to said shaft, and means carried on said last mentioned part adapted to 20 engage a fixed object when actuated manually and independent of the first mentioned part.

6. The combination with a carbide receptacle, a gas generating-chamber, and a 30 gasometer having a gas-bell, a valve controlling the feed of carbide to the gas generating-chamber, a shaft to which said valve is secured, a controlling-lever comprising a lever-member loosely mounted on the shaft 35 and in operative connection with the gas-bell of the gasometer, a lever-member affixed to said shaft, a lock-member normally locking said lever-members together and arranged to permit of disconnecting said 40 lever-members, and a stop-lever carried on said lock-member and adapted to engage a fixed object when said lock-member is moved to disconnect said lever-members.

7. The combination with a carbide-receptacle, a gas generating-chamber, and a 45 gasometer including a gas-bell having a rod provided with a slot therein, of a valve controlling the feed of carbide to the gas generating-chamber, a shaft to which said 50 valve is affixed, and a controlling lever consisting of a lever-member loosely mounted between its ends on said shaft and having its long arm in engagement with the slotted-rod on said gas-bell, a second-lever member 55 secured between its ends to said shaft and having its short arm curved downward, a lock-member comprising a long-arm and a short-arm connected by a connecting arm providing a space to receive the short arm 60 of said first mentioned lever-member when locking the lever-members together, said lock-member having the free end of its short arm pivotally attached to the curved short arm of said second-mentioned lever-

member and the lower edge of its long arm 65 curved to ride over the end of the short arm of said first mentioned lever-member when swung into unlocking-position, and a retractile spring connected at its ends to said second mentioned lever-member and to said 70 lock-member.

8. The combination with a carbide-receptacle, a gas generating-chamber, and a gasometer including a gas-bell having a rod provided with a slot therein, of a valve controlling the feed of carbide to the gas generating-chamber, a shaft to which said valve is affixed, and a controlling-lever consisting of a lever-member loosely mounted between its ends on said shaft and having its long arm in engagement with the slotted-rod on 75 said gas-bell, a second lever-member secured between its ends to said shaft and having its short arm curved downward, a lock-member comprising a long-arm and a short-arm connected by a connecting arm providing a space to receive the end of the short arm of said first mentioned lever-member when locking the lever-members together, said lock-member having the free end of its 80 short arm pivotally attached to the curved short arm of said second-mentioned lever-member and the lower edge of its long arm 85 curved to ride over the end of the short arm of said first mentioned lever-member when swung into unlocking position, a retractile spring connected at its ends to said second mentioned lever-member and to said lock-member, and a stop-member pivotally attached to the upper edge of said lock-member and adapted to swing outward when said lock-member is swung into its unlocking position to engage a fixed object when the second mentioned lever-member is actuated 90 manually.

9. The combination with a gas-bell, and a gas-generating chamber coöperating therewith, of a carbide-receptacle having a feed-hopper, a segmental feed-valve adapted to open and close the mouth of said hopper, a closure pivotally secured to one side of the axis of said hopper and having its upper face conforming to the lower edge of said feed hopper, means to cause said closure to swing against the lower edge of said feed-hopper when said feed-valve is moved to allow a quantity of carbide to escape from said hopper, and mechanism actuated by said gas-bell and adapted to actuate said feed-valve.

In testimony whereof, I have affixed my signature in the presence of two subscribing witnesses.
